DESIGN FOR A TOY VEHICLE

Irving E. Lipton and Louis C. Lochmoeller,
St. Louis, Mo.

Application October 1, 1945, Serial No. 122,430

Term of patent 14 years

(Cl. D34—15)

To all whom it may concern:

Be it known that we, Irving E. Lipton and Louis C. Lochmoeller, both citizens of the United States and residents of the city of St. Louis, in the State of Missouri, have invented a certain new, original, and ornamental Design for a Toy Vehicle, of which the following is a specification, reference being had to the accompanying drawing, forming part thereof.

In the drawing:

We claim:

The ornamental design for a toy vehicle, as shown.

IRVING E. LIPTON.
LOUIS C. LOCHMOELLER.
